UNITED STATES PATENT OFFICE

VICTOR EDWARD LANE, OF BERWICK, PENNSYLVANIA:

TOOL-HOLDER FOR PNEUMATIC HAMMERS.

951,013.

Specification of Letters Patent. Patented Mar. 1, 1910:

Application filed March 10, 1909. Serial No. 482,549.

To all whom it may concern:

Be it known that I, VICTOR EDWARD LANE, a citizen of the United States, and a resident of Berwick, in the county of Columbia and State of Pennsylvania, have invented a new and Improved Tool-Holder for Pneumatic Hammers, of which the following is a full, clear, and exact description.

My invention relates to tool holders for pneumatic hammers, my more particular purpose being to provide a construction adapted to retain the tool in proper working relation to the hammer, allowing the tool all necessary freedom and effectively preventing the tool from being unexpectedly ejected from the hammer so as to cause an accident.

More particularly stated, my invention comprehends a hammer barrel to which is operatively connected a rivet set or tool, by aid of appropriate connections which allow the rivet set or tool to be readily removed, when desired, from the barrel, but prevent such removal occurring accidentally.

Reference is to be had to the accompanying drawings forming a part of this specification, in which similar characters of reference indicate corresponding parts in both the figures.

Figure 1 is a side view, partly in elevation and partly in section, showing part of a hammer barrel and a rivet set extending partly into said barrel and provided with a neck, this view further showing pins which extend radially inward toward said neck, and a band encircling the pins to prevent their unauthorized removal; and Fig. 2 is a vertical central section upon the line 2--2 of Fig. 1, looking in the direction of the arrow, and showing the neck of the tool, and further showing the pins for preventing the removal of the tool from the barrel, this view further showing how the band is fitted upon the barrel in order to hold the pins in position.

At 3 is a cylindrical barrel forming part of a pneumatic hammer.

At 4 is a rivet set which is provided with a stem 5 extending into the barrel 3. This stem is provided with a neck 6 of reduced diameter.

At 7, 8 are pins which are provided with heads 9, 10, the heads being sunken slightly into the barrel 3.

At 11 is a band consisting of a strip of

sheet spring metal bent substantially into the form of a circle. One end of the strip is shown at 12 and is bent slightly inward, entering a notch 13. The opposite end 14 of the band slightly overlaps this notch 13. The band 11 as a whole is sunken slightly into the barrel 3, so that the outer surface of the band is substantially flush with the outer surface of the barrel. The band engages directly the heads 9, 10 of the pins 7, 8 and normally prevents the removal of these pins. Except for the band, however, the pins may be easily removed and the rivet set thereupon released from the barrel. The pins 7, 8 are provided with annular bevels 15, 16, and the stem 5 is provided with beveled shoulders 17, 18, 19 of annular form.

My invention is used as follows: In order to assemble the parts, the stem 5 of the rivet set is extended a little way into the end of the barrel. The pins 7, 8 are next placed in position so that the points of these pins loosely engage, or at least closely approach in position, the outer surface of the neck 6. The band 11 is next placed in position, the portion 12 being slipped into the notch 13 and the end 14 being brought partially over the notch 13. The band being made of spring material clings upon the barrel 3 and causes no inconvenience in handling the hammer. The rivet set 4 is now free to play in the general direction of its axis and when actuated in the usual manner is capable of conferring its power upon the rivet or other object to be driven. In order to remove the rivet set, the operator (using an implement for the purpose, if he so desires) raises the ends 14 of the band 11 and slips this band off, prying the inturned portion 12 out from the notch 13. The pins 7, 8 are next removed, which is easily done as they merely fit neatly in position. The rivet set is now free and can be taken out. If desired, however, the rivet set can be removed from the hammer barrel much more quickly than in the manner above described. The operator, by grasping the rivet set and giving it a quick jerk, can extricate it from the barrel. This is because the bevel 17 rides upon the bevels 15, 16, forcing the pins 7, 8 outwardly so that the rivet set becomes disengaged. In order to replace the rivet set, it is pushed quickly into the barrel so that the annular shoulder 18, being beveled as shown and lodging against the annular bevels 15, 16, on the pins 7, 8, forces these pins apart. In

either taking the rivet set out or putting it back in this manner, the band 11 springs outwardly a little.

While my intention is to prevent the rivet set from being forcibly ejected by any accidental means, I do not intend to prevent it from being removed quickly and at will by the operator, and that, too, without the necessity for taking off the band 11 or removing the pins.

In the construction above described the rivet set is normally held in its working position and is prevented from falling out, in case the barrel of the hammer is pointed downwardly and the rivet set happens not to rest against anything to support it except that it depends from the barrel. The ease with which the rivet set can be removed depends entirely upon the flexibility of the spring band and the angle of the bevels at the inner ends of the pins, and also upon the amount of chamfer given to the annular bevel surfaces carried by the rivet set.

As is well known by persons accustomed to handle pneumatic hammers, there is danger of the rivet set being thrown violently from the barrel, as, for instance, by some unauthorized person pulling the trigger of the pneumatic hammer, or from some accidental disturbance of the trigger or parts affected by the latter. In fact, it is nothing unusual for the rivet set to be ejected so violently that it acts like a projectile and would probably kill a person should it happen to strike him in a vital part. By aid of my invention, however, such an accident can not

readily occur. If the hammer unexpectedly makes a stroke, the rivet set is driven forward a measured distance, just as it would be in striking the working blow, and is stopped by the pins 7, 8. While for convenience I have described the member 4 as a rivet set, it will be understood that I do not limit myself thereby, as many other tools are well known in this art as equivalents for a rivet set of the type shown. Neither do I limit myself to the particular form of the band 11. This band is for some purposes essentially a clip, and it is obvious that clips of other forms may be employed in the relation above described.

Having thus described my invention, I claim as new and desire to secure by Letters Patent:

The combination of a barrel provided externally with a notch, a clip made of spring metal and provided with an inturned portion extending into said notch, said clip having generally a circular form and extending substantially around said barrel, a pin extending radially through said barrel and held in position by said clip, and a rivet set provided with a stem extending into said barrel, said stem being provided with a reduced portion disposed adjacent to said pin.

In testimony whereof I have signed my name to this specification in the presence of two subscribing witnesses.

VICTOR EDWARD LANE.
